UNITED STATES PATENT OFFICE.

JAQUES EDWIN BRANDENBERGER, OF NEUILLY-SUR-SEINE, FRANCE.

ARTIFICIAL TEXTILE FABRIC AND THE PROCESS FOR ITS MANUFACTURE.

1,394,270.

Specification of Letters Patent. Patented Oct. 18, 1921.

Application filed May 18, 1920. Serial No. 382,375.

To all whom it may concern:

Be it known that I, JAQUES EDWIN BRANDENBERGER, citizen of the Republic of Switzerland, and resident of Neuilly-sur-Seine, 5 Seine, France, (post-office address 2 Rue Amiral de Joinville,) have invented a new and useful Artificial Textile Fabric and the Process for its Manufacture, (for which I have filed application in France on May 13, 10 1919,) which improvements are fully set forth in the following specification.

The present invention relates to the manufacture of artificial textile threads and the like.

15 Heretofore, artificial textile fabrics have been woven with threads made from solutions of viscose, cupra-ammonium cellulose, collodion, gelatin, cellulose acetate and the like; but in all such cases the threads have 20 been solid, and the fabrics themselves are heavy, transparent and cold to the touch. According to this invention, however, the threads, instead of being solid, are more or less hollow, due to the presence therein of a 25 series of minute bubbles of air, or some other gaseous fluid which is inert to the cellulose or other viscous solution, arranged side by side; and as the result of the employment of these threads, the fabrics constructed therefrom are very light, opaque 30 and warm to the touch. These characteristic properties may, moreover, be modified as to their degree of intensity by regulating the quantity of bubbles introduced into 35 the threads and, hence, into the fabric, so that it is possible to obtain, for example, a textile fabric having absolutely the same appearance and feel as wool.

The introduction of the bubbles of air or 40 other gaseous fluid into the viscous solution may be effected in any suitable manner; for instance, by injecting the air or gas directly into the solution, by beating up the solution, by the use of emulsifying apparatus, 45 etc., etc.

The emulsion thus obtained is sufficiently permanent to render possible the manufacture of the threads by means of the draw- 50 plates or spinning heads usually employed in the manufacture of artificial silk; but if deemed necessary or desirable, the permanence of the emulsion may be increased by adding to the substances employed other substances such as soap, albumen, gelatin, 55 etc.

The accompanying drawing illustrates

certain forms which the invention may take in practice, as distinguished from the usual form of thread, and various ways in which it may be obtained; but it is to be understood that such showing is given merely by way of example, and imposes no limitation on the invention itself.

In said drawing:

Figure 1 is a side elevation of the ordinary form of thread.

Fig. 2 is a side elevation, partly in longitudinal section, of a thread constructed in accordance with the invention.

Fig. 3 is a vertical cross-section of Fig. 2.

Fig. 4 is a longitudinal section of a thread of viscose containing a succession of bubbles.

Fig. 5 is a similar view of a thread in which the different bubbles unite in forming a continuous bore.

Fig. 6 is a vertical sectional view, more or less diagrammatic in character, of one form of apparatus for producing the emulsion.

Fig. 7 is a diagrammatic side elevation of a spinning or thread-forming device which may be utilized in conjunction with the apparatus represented in Fig. 6.

Fig. 8 is a diagrammatic sectional view of another form of emulsifying apparatus.

Referring more particularly to the drawing, the usual form of filament or thread is represented, on a greatly enlarged scale, in Fig. 1, as previously stated, such filament being solid throughout. In contradistinction thereto, the improved form of thread contains a series of bubbles *a* of air or other inert gaseous fluid such as oxygen, hydrogen, nitrogen, etc., which are disposed side by side within the thread, as indicated in Figs. 2 and 4; the presence of the bubbles being due to the introduction of the gaseous fluid into the viscous solution and the retention of particles of the fluid in the subsequently formed emulsion. Under ordinary conditions, these bubbles will be too small to possess an internal tension sufficient to enable them to swell out the thread, but will be of relatively minute size and will be spaced slightly from each other in the manner indicated in Fig. 4; although if the quantity of air or gas contained in the emulsion is very great, the bubbles may join each other and thus unite in forming a continuous bore *b*, as shown in Fig. 5. It is usual, however, to allow the emulsion, after having been formed, to stand for a

while in order to permit the large bubbles to rise to the surface and break, and then to deliver the emulsion to the spinning head; but even in such case the bubbles contained 5 in the thread may produce a slight swelling, as represented in Fig. 2.

Fig. 6 shows an emulsifying apparatus comprising a receptacle for containing a quantity of the viscous solution *d*, which is 10 preferably viscose and which is whipped up or agitated to effect its aeration by means of a suitable beater *c* driven in any desired manner, the lower portion only of the beater being submerged in the viscose. Any other 15 form of emulsifying apparatus may be used, however; for instance that illustrated in Fig. 8, in which the air or gas is injected into the viscous solution *i* through a nozzle *h* which directs it against the adjacent wall 20 *k* of the receptacle. The latter is provided with two oppositely-extending outlet arms or branches through which the emulsion is discharged.

In either case, the emulsion, after its 25 formation, and after it has stood for a while to permit the large bubbles to rise and break, is delivered in some suitable manner to the drawing or spinning plate or head *e* (Fig. 7); the filaments *f* discharged 30 through the perforations in said plate or head being twisted together to form the final thread or filament.

While the invention has been described above in connection with the formation of 35 continuous filaments or threads, it is to be understood that it is equally applicable to the production of short hairs or threads for power spinning; and that it can also be utilized in the manufacture of films, plates, 40 bands, etc. In any event, the product, whatever its form, can be subjected to the action of dyeing baths in the same way as the ordinary filaments.

I claim as my invention:—

45 1. The herein-described process, comprising the steps of emulsifying a viscous solution and a gaseous fluid which is inert to said solution, and expressing the resultant emulsion through a drawing plate to produce an 50 article containing an internal series of bubbles of said fluid.

55 2. The herein-described process, comprising the steps of simultaneously forming a plurality of continuous filaments, each of which is partly hollow; and thereupon twisting the several filaments together to form a single thread.

60 3. The herein-described process, comprising the steps of simultaneously forming a plurality of continuous filaments, each of which has an internal series of bubbles containing a gaseous fluid which is inert to the substance of which the filament is formed; and thereupon twisting the several filaments 65 together to form a single thread.

4. The herein-described process, comprising the steps of emulsifying a viscous solution and a gaseous fluid which is inert to said solution; expressing the resultant emulsion through a drawing plate to simultaneously form a plurality of filaments, each of which contains an internal series of bubbles of said fluid; and thereupon twisting the several filaments together to form a single thread. 70

5. The herein-described process, comprising the steps of emulsifying a viscous solution and a gaseous fluid which is inert to said solution; allowing the resultant emulsion to stand after its formation has been completed, so as to permit the large bubbles of gaseous fluid to rise to the surface of the emulsion and escape; expressing said emulsion through a drawing plate to simultaneously form a plurality of filaments, each containing an internal series of minute bubbles of said fluid; and thereupon twisting the several filaments together to form a single thread. 80

6. The herein-described process, comprising the steps of emulsifying a viscous solution and a gaseous fluid which is inert to said solution; allowing the resultant emulsion to stand after its formation has been completed, so as to permit the large bubbles of gaseous fluid to rise to the surface of the emulsion and escape; and expressing said solution through a drawing plate to produce an article containing an internal series of minute bubbles of said fluid. 90

7. As a new article of manufacture, a thread or filament composed of a viscous substance having within its interior a series of bubbles of a gaseous fluid which is inert to the viscous substance. 95

8. As a new article of manufacture, a thread or filament composed of viscose having a series of minute air bubbles within its interior. 100

9. As a new article of manufacture, a thread or filament composed of viscose having within its interior a series of minute bubbles of a gaseous fluid which is inert to viscose. 110

10. An article of the character described, comprising a body portion formed of a solidified viscous substance containing within its interior a series of minute bubbles of a gaseous fluid which is inert to the viscous substance, said bubbles being arranged side by side. 115

11. As a new article of manufacture, an artificial silk thread which is partly hollow.

12. As a new article of manufacture, an artificial silk thread containing an internal series of bubbles of gaseous fluid. 125

13. As a new article of manufacture, an artificial silk thread comprising a series of filaments twisted together, each of said filaments being partly hollow. 130

14. As a new article of manufacture, an artificial silk thread comprising a series of filaments twisted together, each of said filaments containing an internal series of bubbles of gaseous fluid.

15. The herein-described process, comprising the steps of emulsifying a viscous solution and a gaseous fluid which is inert to the viscous solution; and then expressing the emulsion through a drawing plate to form a filament wherein a series of bubbles of said fluid are entrained.

16. The herein-described process, comprising the steps of emulsifying a viscous solution and a gaseous fluid which is inert

to the viscous solution; allowing the resultant emulsion to stand after its formation has been completed, so as to permit the large bubbles of gaseous fluid to rise to the surface of the emulsion and escape; and then expressing the emulsion through a drawing plate to form a filament wherein a series of bubbles of said fluid are entrained. 20

In testimony whereof I have signed this specification in the presence of a subscribing 25 witness.

JAQUES EDWIN BRANDENBERGER.
